UNITED STATES PATENT OFFICE.

BOWEN R. GOVER, OF DETROIT, MICHIGAN.

DESIGN FOR A SIGNAL DEVICE.

Application filed October 4, 1923. Serial No. 7,397. Term of patent 14 years.

To all whom it may concern:

Be it known that I, BOWEN R. GOVER, a citizen of the United States, residing at Detroit, in the county of Wayne and State of Michigan, have invented a new, original, and ornamental Design for Signal Devices, of which the following is a specification, reference being had to the accompanying drawing, forming a part thereof.

Fig. 1 is a front or plan view of my signal devices showing my new design and more particularly its ornamental features.

Fig. 2 is a view of the bottom of the device.

Fig. 3 is a side view, the interior signaling and lighting features being indicated by dotted lines.

I claim:

The ornamental design for a signal device as shown.

BOWEN R. GOVER.
